UNITED STATES PATENT OFFICE.

ERVIN D. SWAN, OF GLEN RIDGE, NEW JERSEY, ASSIGNOR TO LIDGERWOOD MANUFACTURING COMPANY, OF NEW YORK, N. Y., A CORPORATION OF NEW YORK.

CABLEWAY.

1,226,405.

Specification of Letters Patent. Patented May 15, 1917.

Application filed June 7, 1913. Serial No. 772,253.

To all whom it may concern:

Be it known that I, ERVIN D. SWAN, a citizen of the United States, residing at Glen Ridge, in the county of Essex and State of New Jersey, have invented certain new and useful Improvements in Cableways, of which the following is a specification.

My invention relates broadly and generally to new and useful improvements in cableways, and more particularly to those of the portable type employed in logging operations. The invention is hereinafter shown and described in connection with the portable type of cableway in which is employed a main cable secured at one end to a tail-tree, and at the other end to a portable head support or tower. These systems usually include a load carriage adapted to travel on the main cable, an outhaul rope for propelling the carriage to a point adjacent where the load is to be taken, a skidding and hoisting line passing over the carriage for lifting the load and inhauling the carriage and load, and a rope for pulling slack in the inhaul or skidding line to facilitate attachment of said line to the load. My present invention contemplates an improved means for supporting the main cable on the head tower, and for elevating the same into operative position and adjusting it at the proper elevation.

While, as above stated, I show and describe the invention in connection with a particular type of cableway, I desire it understood that the invention is not limited in its use to a portable type of cableway, as it is adapted for use in connection with permanent, as well as portable, types, but I have shown it in connection with the particular type of cableway to which I have adapted it.

The invention consists in the construction and combination of parts to be more fully described hereinafter, and the novelty of which will be particularly pointed out and distinctly claimed.

I have fully and clearly illustrated my invention in the accompanying drawings to

be taken as a part of this specification, and wherein—

Figure 1 is a view in side elevation of a portable head tower to which my invention is applied;

Fig. 2 is a plan view of a winding and holding engine employed in connection with my invention;

Fig. 3 is a view in side elevation, partly in section, of an improved head block and tension or pull-reducing device for supporting the main cable;

Fig. 4 is an edge view of the block or device shown in Fig. 3;

Fig. 5 is a detailed top plan view of the supporting head for connecting the main cable and main cable tension guy to the head tower.

Referring to the drawings by characters of reference, and particularly to Fig. 1:

A designates generally a portable head tower apparatus consisting of a truck or platform 1, supported upon suitable running wheels 2, adapted to travel upon a trackway 3. Supported on this platform 1, is a vertical supporting frame 4, on the upper end of which is fulcrumed, as at 5, the supporting spar or tower 6, said tower having a projecting part 7 extending below its fulcrum to the lower end of which part 7 is connected a running connection 8, the line 9 of which passes to a winding drum 10 on an engine 10, by means of which running connection the spar is elevated to the position shown in Fig. 1, and held in elevated position.

Supported on the head tower are blocks 11, 12, 13, over which pass respectively the 85 outhaul line 14, skidding and inhaul line 15 for operating the carriage (not shown), and the slack-pulling line 16, said lines passing respectively to drums 17, 18, 19 of the wind- 90 ing engine 10.

The parts just described specifically form no part of my present invention except in so far as they may enter into combination, and for this reason I do not deem it necessary to make a more detailed description

than that just given, as it will be sufficient for a proper understanding of my present invention.

Mounted upon the upper end of the head tower is a swivel collar 20, adapted to rotate horizontally about the tower, and connected by a swivel or link connection 21 to this collar is a combined block and tension or pull-reducing device 22, for supporting the main cable 23. Pull on the main cable is opposed, and the spar 6 steadied and gaged, by a split anchorage, the members of which are designated at 24-24, each being adapted to be secured at one end to an anchorage off the portable apparatus, and connected at the opposite ends to a running connection 25, which is swiveled, as at 26, to the swivel collar 20 heretofore described. The line 25^a from this running connection 25 passes down to the drum 27, by means of which the running connection may be taken up or let out to regulate the resistance afforded by the spar to the pull of the main cable.

25 I will now proceed to specifically describe the block 22 for supporting the main cable.

The block 22 comprises two side plates 28-28 spaced from each other, and connected at one end by a connection member 29, which is rotatably suspended on one of the members of the swivel connection 21. The said side plates 28 are disposed in parallel spaced relation, and between them is arranged a pulley sheave or drum 30 mounted 35 to rotate freely upon a bearing pin 31, the opposite ends of which are supported by the said side plates 28. This pulley sheave 30 or drum is provided with a peripheral groove 32 having an elliptical bearing face 33, on which the main cable is adapted to 40 be wound for a plurality of turns, as will be hereinafter set forth. Rigid with the said faces of the sheave 30 are annular sets of ratchet teeth 34, with which coöperate spaced 45 pawls 35 rigidly mounted upon and connected by a sleeve 36, which is pivoted on a pivot pin 37 having its ends fixed in the side plates 28-28 of the block. Suitable means is provided for normally urging the 50 engaging ends of the pawls 35 into contact with the ratchet teeth 34, this object being accomplished preferably by a weight 38, secured to the sleeve 36, on the opposite side of the pivot pin 37. The ratchet teeth are 55 so directed that the sheave 30 will be held against clockwise movement under strains exerted thereon by the main cable, the pawls 35 engaging the ratchets 34 beneath the pin 31, as clearly shown in Fig. 3 of the drawings. The pawls are maintained in proper 60 engagement with the ratchet teeth against lateral displacement therefrom by means of annular side flanges 39, which project ra-

dially of the sheave beyond said ratchet teeth, as shown in Figs. 3 and 4 of the drawings. According to the present embodiment of my invention, the main cable is wrapped around the sheave 30 for a plurality of turns and is then carried down and wound upon a drum 40, which drum is revolved under power to take up the main cable until the proper elevation thereof is reached, said drum forming part of the hoisting engine which will now be described.

41-41 designate side frames in which is 75 journaled a power shaft 42, carrying crank disks 43, connected by pitmen 44, to pistons of engine cylinders 45. This shaft 42 has loosely mounted thereon a pinion 46 adapted to be clutched to said shaft to turn therewith by a positive clutch 47, slidably mounted on the shaft 42 and adapted to be operated in any suitable manner. The pinion 46 meshes with a gear 48, fixed to a drum shaft 49, upon which shaft is mounted the 80 drum 27, heretofore mentioned, said drum 27 being movable longitudinally of the shaft 49 by means of a thrust mechanism 50, to connect said drum to the gear 48, by means of friction clutch surfaces 51, 52, carried 85 by the drum and said gear 48, respectively. The gear 48 is provided on its side opposite to the clutch face 52 with a circular series of ratchet teeth 53, adapted to be engaged by a pawl 53^a, to hold the drum against rotation when the latter is frictionally connected to the gear 48. The opposite end of the drum 27 carries an annular braking surface 54, to receive a band brake 54^a. Loosely mounted on the shaft 49 is a gear 55 adapted 90 to be clutched to the shaft to turn therewith by means of a clutch 56, operated in any suitable manner, said gear 55 meshing with a large gear 57, on one end of the drum 40, heretofore described. The drum 40 carries 100 at one end a circular series of ratchet teeth 58, adapted to be engaged by a pawl 59, whereby said drum may be held against rotation under pull of the main cable. Fixed to the shaft 42 is a pinion 60 meshing with 105 a gear 61, on a shaft 62, said gear 61 being located between the drums 63, 64, and adapted to be connected to either, or both, of said drums by frictions 63^a, 64^a. The drums 63, 64, respectively, operate the changing lines, 110 not shown, for laying out the main cable between the head-tower and the tail-tower before said main cable is elevated. Both of the drums 63, 64, may be provided with suitable braking faces 65, 66, with which coöperate band brakes, not shown. I do not deem it necessary to go into any further detailed description of this hoisting engine, as the description given will be sufficient to show the manner in which the drum 40 is 115 operated for taking up or paying out the 120 125

main cable. The drum 40 may also be provided with a braking surface 40^a, with which co-operates a band brake 40^b for retarding rotation of the drum when it is disconnected from the shaft 49, and released from its pawl and ratchet lock to pay out the main cable. By the above invention I provide an efficient means whereby a rope under heavy loads may be held by power of the engine drum 10 very much below the load exerted on the rope by the carriage and the weight of the rope. For example, in an installation employing a main cable of one and one-quarter inch diameter, I would make the sheave 30 substantially thirty inches in diameter, and the groove 32 about six inches in width, and would wrap the rope about said sheave four times before the rope would be attached to the winding drum 40. Under such an arrangement, when the sheave 32 is locked against rotation by the pawl being engaged therewith a pull or a load on the main cable of say 134,000 pounds would be reduced to approximately 27,000 pounds on the holding drum. This is accomplished by the elliptical or curved form of the groove of the sheave 30, which causes the turns of the rope to frictionally engage each other and the sheave, and the friction caused by the number of wrappings of the main cable on the sheave and the large diameter of the sheave. In operation the main cable is wrapped around the sheave 30 for the required number of turns, and is then carried down and wound about the holding drum 40, which, being connected through the clutch mechanism to the driving shaft of the engine, is operated to take up the main cable until the latter reaches the proper elevation. The pawls 35 then engage with the ratchet teeth 34 to lock the sheave against rotation permitting the paying out of the main cable, and the pawl 59 is thrown over to engage the ratchet teeth 58 on the holding drum to prevent rotation of the latter to pay out the main cable. When it is desired to lower the main cable the drum is disconnected from the driving shaft, the sheave 30 is released from the pawls 35, and the holding drum is permitted to rotate under the restraint of its brake until the main cable is lowered to the desired position.

I provide means for conveniently disengaging the pawls 35 from the ratchet teeth 34, said means preferably consisting of a pull cord 38, passing over a pulley or guide roller 38^b, arranged between the plates 28 and turning on a cross pin 38^c fixed in said plates, one end of said cord being connected to the pawl weight 38, as at 38^a, and the other end depending to a point of easy access to the operator. It will be understood that a pull on this cord will lift the weight

38, thereby throwing the pawls downward out of engagement with the ratchets. This 65 is desirable when the cable is to be paid out for any reason.

What I claim and desire to secure by Letters Patent of the United States is:—

1. In a cableway, in combination, a support, a cable supported thereby and exerting its load thereon, a winding drum upon which the cable is wound, and means whereby the load of the cable on the drum is less than the load of the cable on the support. 70

2. In a cableway, in combination, a support, a cable supported thereby, a friction holding means for connecting the main cable to said support but permitting passage of the cable in either direction, and a drum 80 upon which the cable is wound.

3. Supporting means for one end of a cableway, comprising an elevated support, a rotatable member swiveled on said support and adapted to have a cable pass over the same, and means for locking said member against rotation in a direction taken by the cable in being paid out.

4. Supporting means for one end of a cableway, comprising an elevated support, a 90 rotatable member supported on said support and adapted to have a cable pass over the same, and means for locking said member against rotation in a direction taken by the cable being paid out but permitting rotation 95 of the member in the opposite direction said means comprising a weighted member normally in locking position.

5. In a cableway, in combination, a support, a rotatable member having swivel connection with said support, a winding drum, a cable passing over said rotatable member and wound on said drum, and means for locking the said rotatable member against rotation in a direction to pay out the cable. 100

6. Supporting means for one end of a cableway, comprising an elevated support, a rotatable member supported on said support and adapted to have a cable pass over the same, a pawl and ratchet for locking said 110 member against rotation in a direction taken by the cable in being paid out, said pawl being weighted so as to be normally held in engagement with said ratchet to lock the latter, and a line connected to the weighted 115 part of the pawl to lift the latter out of engagement with the ratchet to permit the cable to be paid out.

7. In a cableway, in combination, a support, a sheave on said support, a winding 120 drum, a cable rove in a plurality of turns about the sheave and wound on said drum, and means for locking the sheave to prevent rotation of the sheave to pay out the cable.

8. In a cableway, in combination, a support, a sheave on said support, a winding 125

drum, a cable rove in a plurality of turns about the sheave and wound on said drum, and pawl and ratchet mechanism to prevent rotation of the sheave in the direction to pay out the cable.

5. In a cableway, in combination, a support, a cable, means for supporting the cable from said support, a drum upon which the cable is wound, and friction means for reducing the load of the cable exerted on the drum.

10. In a cableway system, a support, a main cable, a pulley supported by said support and over which said main cable passes, a winding drum upon which the main cable

is wound, and means for reducing the main cable load on the drum.

11. In a cableway system, a support, a main cable passing over said support, a power drum on which said cable is wound, 20 and means whereby a load on the main cable is sustained by a smaller force exerted by the winding drum.

In testimony whereof I have hereunto signed my name in the presence of two sub- 25 scribing witnesses.

ERVIN D. SWAN.
